UNITED STATES PATENT OFFICE.

JOHN PADDOCK HUGGINS, OF SYDNEY, NEW SOUTH WALES, AUSTRALIA.

DESIGN FOR A FOLDING CABINET-TABLE FOR A SEWING-MACHINE.

49,647.

Specification for Design.

Patented Sept. 12, 1916.

Application filed July 3, 1916. Serial No. 107,469. Term of patent 7 years.

To all whom it may concern:

Be it known that I, JOHN PADDOCK HUGGINS, a citizen of the United States of America, residing at Harris street, Sydney, New South Wales, Australia, have invented a new, original, and ornamental Design for a Folding Cabinet-Table for a Sewing-Machine, of which the following is a specification, reference being had to the accompanying drawing, forming part thereof.

The figure is a perspective view of a fold-

ing cabinet for a sewing machine, showing my new design.

I claim:

The ornamental design for a folding cabinet table for a sewing machine as shown.

JOHN PADDOCK HUGGINS.
